UNITED STATES PATENT OFFICE

2,583,106

LIQUID PACKAGING MACHINE

Elias Kayat, Hamilton, Ontario, Canada, assignor
to Perga Containers Limited, Hamilton, Ontario, Canada

Application January 12, 1948, Serial No. 1,753

15 Claims. (Cl. 226—94)

1

This invention relates to a machine for automatically filling and sealing flexible liquid containers such as wax impregnated cardboard cartons or the like, and the principal object of the invention is to provide an extremely compact fully automatic and thoroughly reliable high capacity machine which will maintain a positive feed of empty liquid-receiving cartons to the nozzles of a filler mechanism operable in synchronism with the feed mechanism to fill the cartons, and which will thereafter automatically fold and seal and discharge the cartons in a continuous stream ready for delivery to the customer or the merchandiser.

A further and important object is to provide an economical fully automatic machine for filling and sealing flexible liquid containers in which, the action of the component mechanisms are accurately synchronized to ensure proper movement for filling, sealing and handling of the containers to eliminate wastage and loss of time due to a failure in the operation sequence or rupture or improper seal of the container.

A still further important object is to provide a compact fully automatic cardboard carton filling machine in which the component mechanisms are synchronized and operated off a single power source.

A still further object is to provide an automatic cardboard carton filling machine in which an interruption of delivery of the cartons from the magazine to the feeder mechanisms will automatically stop the machine.

A further object is to provide a carton filling machine which can be readily and quickly adjusted to handle different sizes of cartons.

A further object is to provide a novel form of gripper mechanism to select and deliver a single carton from a stack of carton empties to the feed mechanism.

A further object is to provide a novel form of carton magazine which will operate in synchronism with the feed mechanism to position the bottom carton of a carton stack for selection by the gripper mechanism and will retain the remainder of the stack securely against withdrawal to ensure that the cartons are fed singly to the filling apparatus.

A further object is to provide a novel form of sealing mechanism which will ensure an hermetic seal of the cartons upon completion of the filling operation.

A still further object is to provide a machine wherein component units can be quickly removed and replaced for shipping and for servicing.

2

A still further object is to provide a novel form of feeder mechanism which will intermittently advance the cartons accurately to the successive stages of operation of filling and sealing and will adequately support the cartons during movement to prevent tipping and yet will not in any way damage or deform the cartons nor permit the carton feed to become jammed.

The principal feature of the invention consists in providing a single extremely compact machine incorporating on a single bed frame mechanisms for selecting a carton from a supply stack, feeding the carton to a liquid filling device, folding the mouth of the carton and finally effecting an hermetic seal of the carton mouth, the mechanisms being arranged to operate in co-ordinated synchronism to effect automatically the complete sequence of operations.

A further important feature consists in operating all the mechanisms of the machine from a single power source to ensure maintenance of synchronism.

A further important feature consists in mounting the component mechanisms for ready removal and replacement.

A further important feature consists in providing a protector device operable upon interruption of delivery of cartons from the supply stack to the feeder mechanism to stop the machine.

A further important feature consists in providing a novel form of feed mechanism for intermittently advancing the cartons comprising a plurality of spaced yoke members for engaging the cartons adjacent the top, the yoke members being rockably mounted for movement into and out of engagement with the cartons and being arranged to reciprocate in unison longitudinally of the machine, the rocking movement of the yokes being synchronized with the reciprocating movement whereby the yokes are in engagement with the cartons upon the forward stroke of their reciprocating motion.

A further important feature consists in providing a carton magazine having longitudinal side rails, the spacing of which can be adjusted to accommodate various sizes of cartons and which are arranged for mutually inward and outward movement to provide a squeezing action, and providing a latch member for retaining the bottom carton of a carton stack placed in the magazine during the interval the magazine sides are in their outward position, the latch and side rails of the magazine being synchronized with the feeder mechanism whereby the magazine sides

move inwardly to grip and retain the carton stack in position while the latch member opens to free the bottom carton of the stack at the instant a carton is required to be delivered to the feeder mechanism of the machine.

A further important feature consists in providing a reciprocating gripper arm for delivering cartons from the magazine to the feeder mechanism, the gripper arm having a spring-operated jaw which positively grips the bottom edge of the bottom carton of the carton stack and firmly retains the carton during delivery to feeder mechanism, the jaw upon completion of delivery of the carton automatically releasing its grip.

A further feature of the invention consists in providing a filler mechanism employing a piston operable to discharge a measured quantity of liquid and operate through a novel cam-actuated rocker arm, means being provided to adjust the point about which the rocker arm pivots to change the piston stroke and hence the quantity of liquid discharged.

A further important feature consists in providing folding mechanisms for folding the cartons prior to sealing, the folding mechanisms being removably mounted for replacement to permit similar units designed to fold different sizes of cartons to be quickly interchanged therewith.

A further and important feature consists in providing a novel water-cooled electrically heated pressure sealer mechanism to close and seal the mouth of the cartons with an hermetic seal, the temperature of the sealer being accurately controlled to provide consistency in the seals, the cartons upon being sealed being subjected to a cooling liquid spray to harden the seal before they are removed and handled.

Referring to the accompanying drawings,

Figure 1 is a front elevational view of my complete machine.

Figure 2 is an end elevational view of the machine shown in Figure 1 taken from the feed end and with the carton magazine removed.

Figure 3 is a rear elevational view of my machine, while Figure 4 is a plan view of my machine.

Figure 5 is an enlarged part elevational part sectional view of the carton magazine illustrating the magazine adjustments and the toggle arrangement for operating the magazine bars to periodically grip and release cartons arranged in the magazine.

Figure 6 is an enlarged side elevational view of the gripper mechanism for carrying cartons from the magazine to the feed mechanism.

Figure 7 is an elevational view of the carton feeding mechanism illustrating the manner in which the carton-engaging yokes are rocked into and out of engagement with the cartons.

Figure 21 is a side elevational view of the overlap folder bars shown in Figure 20.

Figure 22 is a front end elevational view of the overturning device shown in Figures 20 and 21 and illustrating its relation relative to the machine table and carton feed mechanism.

Figure 23 is a side elevational view of one form of carton sealing mechanism which can be used with my machine.

Figure 24 is a rear elevational view of the sealer shown in Figure 23.

Figure 25 is a plan view of the sealer illustrated in Figures 23 and 24.

Figure 26 is a front elevational view of the sealer.

Figure 27 is a plan view of an alternative and preferred form of carton sealing mechanism for use on my machine.

Figure 28 is a side elevational view of the sealer illustrated in Figure 27, and showing its relation relative to the machine table and the cam mechanism for operating the sealer jaws.

Figure 29 is a vertical sectional view taken on the line 29—29 of Figure 27 and illustrating the construction of a typical jaw of the sealer.

Figure 30 is a vertical sectional view taken on the line 30—30 of Figure 27.

Figure 31 is a sectional view taken on the line 31—31 of Figure 28 and illustrating the arrangement of the heater within the sealer jaw.

Figure 32 is a plan view of the jaw section shown in Figure 31 with the cover plate broken away disclosing the wiring connections for the heater element.

Referring to the accompanying drawings, the table or bed plate 1 of the machine is supported by A-shape legs 2, as particularly shown in Figures 2 and 1. The bed plate 1 has a right angularly downwardly extending portion 3 which extends the length of the bed plate across the front of the machine.

Arranged at one end of the bed plate is the driving motor 4 mounted in a slide 5 so that its position longitudinally of the machine may be altered by a control wheel 6. The motor 4 is arranged to drive a pulley 7 journalled in a frame 8 supported on the bed plate, and the shaft of this pulley 7 drives, through suitable reduction gearing (not shown) a shaft 9 extending longitudinally of the bed plate and journalled in suitable bearings 10 arranged adjacent the ends of the bed plate and spaced thereabove.

A shaft 11 extending longitudinally of the bed plate and arranged beneath the bed plate is journalled in suitable bearings 12 secured to the bed plate portion 3 and arranged at intervals along the length of the shaft.

The shaft 9, which may be considered the main drive shaft, carries a gear 13 at one end which meshes with an idler gear 14 journalled on the end of the bed plate 1 and this intermediate gear 14 meshes with a gear 15 mounted on the end of the shaft 11 to rotate this latter shaft.

The shafts 9 and 11 carry the various cams for effecting the operation of the various component mechanisms of the machine to be presently described.

Referring to Figures 1 to 3, the magazine for holding the empty cartons 16 is arranged at one end of the bed plate 1 and is supported on a vertical somewhat channel-shaped frame 17 which carries a second frame 18 which extends laterally from the frame 17 to project out beyond the forward edge of the bed plate as formed by the right angularly downwardly extending portion 3.

The supporting face 19 of the frame 18 is inclined at an acute angle to the upper surface of the bed plate and mounted on this face 19 is the magazine frame 20 which is in the form of a reverse seat, as clearly shown in Figure 5.

Secured to the inner bottom portion of the frame 20 is a longitudinal plate or rail 21 which extends upwardly from the magazine frame, as shown in Figure 3, and forms the bottom support rail for a stack of empty cartons inserted into the magazine.

As shown in Figure 5, pivoted adjacent the upper outer corner of the frame 20 at 22 is a curved downwardly extending arm 23 which is provided with a short upward extension 24. An adjustable slide plate 25 arranged at the end of the arm 23 and extending at right angles thereto carries at its inner end the outer side rail or plate 26 of the magazine.

Arms 27 and 28, similar to the arm 23, are pivoted as at 29 and 30 respectively adjacent the inner upper corner and inner lower corner of the magazine frame 20 and carry the upper side rail 31 at the inner side rail 32 respectively of the magazine. Again the rails 31 and 32 are carried on slides 33 and 34 respectively which are arranged at right angles to the arms 27 and 28 respectively and are adjustable for spacing the rails carried thereby.

To permit longitudinal adjustment of the rails 26, 31 and 32 the slide plates 25, 33 and 34 are formed of slotted right angular extensions 35 arranged at their inner ends, and the rails carry studs extending through the slots of the slide extensions 35, the rails being clamped to the slide extensions by the wing nuts 36.

Rigidly connected to the arm 27, either as an integral part thereof or keyed to the same pivot shaft 29, is an outwardly extending arm 37 provided with an upwardly extending portion 38 and a downward extension 39.

A link 40, pivotally connected to the extension 38 of the arm 27 and the extension 24 of the arm 23, serves to transmit movement of the arm 37 to the arm 23, while a link 41 connected between the downward extension 39 of the arm 37 and an extension 42 of the arm 28, serves to transmit motion from the arm 37 to the arm 28. The movement of the arm 37 is effected through

the downwardly extending connecting rod 43 pivoted to the outer end thereof as at 44.

Referring to Figure 2, the connecting rod 43 is pivoted at its lower end adjacent the centre of a rocker arm 45 journalled at its inner end on a shaft 46 connected between the vertical flanges of the channel frame 17. The outer end of the rocker arm 45 carries a roller 47 which engages a cam 48 carried on the main drive shaft 9.

Movement of the connecting rod 43 through the cam action of the cam 48 engaging the roller 47 effects a periodic inward and outward movement of the upper rail 31 and the side rails 32 and 26 through the links 41 and 40 respectively. Thus a periodic squeezing and releasing of the cartons arranged between the rails of the magazine is accomplished.

To enable the movement of the magazine rails to be manually accomplished the extension 42 of the arm 28 is elongated to provide a convenient handle.

Referring to Figures 1, 3 and 6, the mechanism for controlling the feed of the cartons to the lower end of the magazine comprises a latch member 49 having a stepped lower end 50 arranged to normally engage the bottom of the lowermost carton in the magazine to block its further downward movement. The latch member 49 is carried on a pivot shaft 51 journalled in the frame.

Connected to one end of the shaft 51 is a horizontal arm 52 pivotally connected at its end to a vertical connecting rod 53 pivoted at its lower end to the end of a rocker arm 54 journalled intermediate its length on the shaft 46.

The rocker arm 54 carries on its outer end a roller 55 adapted to engage a cam 56 carried on the shaft 9. The cam action produced between the roller 55 and cam 56 effects a periodic rocking of the latch member 49 from the solid to the dotted line position of Figure 1.

A tension spring 57 acting downwardly upon the arm 54 maintains the roller 55 in engagement with the surface of the cam 56.

Secured to the latch pivot shaft 51 is a rearward extension 58 adapted to enter a notch in the end of a link 59 when the link is swung to the dotted line position of Figure 1, and with the link engaging the latch extension 58 the latch is prevented from moving downwardly out of its normal position to prevent freeing of the lowermost carton for feeding to the machine.

Under normal operating conditions the link 59 is swung to the solid line position of Figure 1.

Secured to the latch 49 is an arm 60 which extends beyond the end of the latch 49 and has its outer upper edge curved to form a cam surface 61. This arm 60 is disposed on the inner face of the latch 49 and lies in the same vertical plane as the cam surface 62 of a member 63 secured to the frame 17 as shown in Figures 1 and 6.

The gripper arm 64 for carrying cartons from the magazine to the feed mechanism of a machine to be presently described is pivoted at one end to a bracket 65 secured to the frame 17. The free end of the gripper arm 64 is in the form of a jaw having the lower jaw member 66 pivoted at 67 to an extension 68 of the upper or opposing jaw portion 69 formed integral with the gripper arm. A spring 70 serves to maintain the jaw members 66 and 69 in the closed position.

Arranged on the inner face of the lower jaw member 66 is a roller 71 which is adapted to engage the cam surfaces 61 and 62 of the arm 60

and member 63 respectively to open the jaw by swinging the lower jaw member 66 away from the opposing member 63 at the requisite instance to permit the jaw to grip the lowermost carton in the magazine and to release the carton when deposited on the feed platform of the machine.

The operation of the gripper arm 64 is accomplished through the pitman 72 connected eccentrically to the fly wheel 73 carried on a shaft 74 extending through the downwardly extending portion of the bed plate 1 and carrying on its inner end a gear 75 meshing with a gear 76 arranged on the shaft 11 below the bed plate.

The action is such that as the gripper arm moves upwardly its roller 71 engages the cam surface 81 of the arm 60 opening the gripper jaws to receive the bottom edge lip of the lowermost carton in the magazine. Simultaneously the latch member 49 and the arm 60 have been moving downwardly to free the lowermost carton and to permit the gripper jaw to close on the bottom carton lip.

The movement of the magazine rails 26, 31 and 32 is also so co-ordinated that the rails move inwardly to grip the remainder of the cartons while the bottom carton is being released and is being pulled downwardly by the return movement of the gripper arm.

Near the bottom of the stroke of the gripper arm the roller 71 engages the cam surface 82 of the member 63 to again open the gripper jaws at the instant the carton is placed on the platform of the feed mechanism.

The mechanisms for feeding the cartons periodically longitudinally of the table to the various operation stations is illustrated in Figures 1 to 4 and Figure 7. Figures 1 and 2 show the platform 77 on which the cartons are deposited by the gripper arm 64 and along which they are adapted to be slid as a length of angle iron arranged longitudinally of the bed plate 1 and supported for vertical adjustment adjacent the ends by bars 78 slidably held in clamps 79 carried by the brackets 80 secured to the bed plate portion 3.

Also secured to the bed plate portion 3 adjacent the ends are brackets 81 in which are journaled a pair of spaced horizontal shafts 82 and 83. The outer shaft 83 has a plurality of spaced arms 84 secured thereon and extending upwardly therefrom.

Each of the arms 84, with the exception of the last arm adjacent the motor end of the bed plate, carries a curved yoke portion 85 which projects inwardly and is adapted to receive one of the cartons being fed along the feed platform 77. The end arm 84 carries an inward projection 86 which extends only from the trailing edge to ensure that there will be no obstruction to the delivering of the carton by the last arm onto the belt conveyor 87 which is driven through the pulley 88 and around the idler pulleys 89 through the gear 90 keyed on the shaft of the pulley 88 and meshing with a gear 91 carried by the shaft 11 arranged on the underside of the bed plate.

Connected to the outer shaft 83 of the feed mechanism is a yoke member 92 and this yoke member is connected through a pitman 93 to a fly wheel 94, the end of the pitman being pivoted eccentrically of the fly wheel.

This fly wheel 94 is keyed on a shaft extending through the downwardly extending bed plate portion 3 and arranged on the inner end of this shaft is a gear 96 which meshes with a gear 97 carried on the shaft 11. Thus through operation

of the fly wheel and pitman 93 the shaft 83 carrying the arms 84 is reciprocated longitudinally of the bed plate.

During this reciprocation of the shaft 83 a 5 rocking motion inwardly and outwardly of the bed plate is occurring.

As illustrated particularly in Figures 7 and 1, the inner shaft 82 carries a toothed segment 98 which meshes with a correspondingly toothed 10 segment 99 secured to the outer shaft 83 of the feed mechanism.

A forked member 100 secured to the shaft 82 and depending therefrom slidably engages a block 101 arranged in its fork and slidably mounted on a rod 102 supported between an arm 103 rotatably mounted on a rod 104 and a rocker arm 105 in the form of a bell crank pivoted on the same rod 104 suitably supported between brackets 106 secured to the downwardly extending portion 3 of the bed plate.

The inner end of the bell crank or rocker arm 105 carries a roller 107 which engages a somewhat sector-shaped cam 108 mounted on the drive shaft 11. Thus through the cam action 25 produced by the roller 107 engaging the cam surface of the cam 108 the bell crank 105 is rocked about its pivot provided on the rod 104, causing a rocking of the forked member 100 through the block 101 to effect rocking of the shaft 82 and through the toothed segments 98 and 99 rocking of the shaft 83.

The inner shaft 82 carries uprights 109 between which suitable bars 110 extend to engage the cartons and maintain same in the centre of the 30 feed platform 77.

The timing of the feed mechanisms is such that at the instant a carton is deposited on the platform 77 by the gripper arm 64 the pitman 93, through movement of the fly wheel 94, has moved 40 the shaft 83 to the magazine end of the bed plate. At this instant the forked member 100 and the block 101, which have been slid along the rod 102 to adjacent the bell crank 105, have been 45 swung outwardly of the bed plate by virtue of the bell crank 105, moving the rod 102 through the cam action of the cam 108 away from the bed plate portion 3 to swing the arms 84 and uprights 109 carried by the shafts 83 and 82 respectively outwardly of the feed platform 77.

50 As the carton is released by the gripper arm 64 the cam action of the cam 108 and roller 107 is such as to permit the rocker shafts 82 and 83 to rock inwardly under action of the spring 111, whereby the yoke portion 85 of the arm 84 adjacent the magazine engages on either side of the carton which is prevented from being pushed laterally off the feed platform by the bars 110 carried by the uprights 109 of the inner rock shaft 82.

55 The pitman 93 through the action of the fly wheel 94 then moves the shafts 82 and 83 longitudinally of the machine and the carton is carried, through the engagement with the yoke portion 85 of the arm 84, a distance along the feed platform 77 corresponding to the stroke of the pitman 93. During this interval the arms 84 are maintained in their carton-engaging position, but upon completion of the end of the stroke of the 60 pitman 93 the yoke-carrying arms 84 are rocked outwardly of the bed plate through the mechanism described and are retained in this outward position during the return stroke of the pitman 93.

75 The motion of the carton engaging and feeding

arms 84 is rectilinear moving longitudinally of the machine from the magazine end towards the motor while in the innermost carton-engaging position, then swinging out from the machine upon reaching the end of the feed stroke and moving again longitudinally of the machine while swung outwardly therefrom from the motor end to the magazine end until the end of the longitudinal return stroke is reached at which time the arms again swing inwardly to start the repeat cycle.

Thus the cartons are fed the stroke of the pitman 93 at fixed intervals and the operating stations of the filler and sealing mechanism to be described are located so that the cartons are deposited in correct position for the operation upon completion of the feed stroke. The cartons are of course stationary during the interval that the arms 84 are swung outwardly from the bed plate and are moving toward the magazine end thereof.

To ensure that the cartons are properly guided along the feed platform 77 during the feed movements, spaced guide bars 110 are arranged above the feed platform and extend longitudinally thereof, being supported at intervals along their length.

As a safeguard to stop the machine and prevent wastage in the event that the last carton has been drawn from the magazine or for some reason cartons are not being delivered to the feed platform 77, I provide a feeler mechanism for interrupting the supply to the driving motor 4. As illustrated particularly in Figure 2, this feeler mechanism comprises an arm 113 pivoted at 114 at one end and carrying intermediate its length a roller 115 adapted to engage a cam 116 formed with a groove in one portion of its periphery.

The arm 113 carries at its free end an extension 117 adapted to engage the top surface of a carton, while the pivoted end carries an extension 118 adapted upon downward movement of the feeler arm 113 to actuate a switch mechanism 119 to interrupt power to the motor 4.

As illustrated in Figure 2, when a carton is in position on the feed platform 77 and the extension 117 engages the upper edge of the carton the arm 113 will be held up off the cam 116 at the instant its grooved portion is opposite the roller 115 and the switch 119 will not be actuated. In the event a carton is not in position on the feed platform however, the roller 115, on following the cam surface of the cam 116, will permit the arm 113 to move downwardly about its pivot, causing the extension 118 to break the motor circuit.

The machine is specifically intended for packaging milk and the cartons delivered from the magazine are of wax-impregnated cardboard to form a liquid-tight container.

The filler mechanism as illustrated in Figures 1 and 3 and more particularly in Figures 8, 9, 10, 11 and 12 operates to discharge measured quantities of liquid from the gravity tank 120 into the cartons during the interval they are stationed below the filler discharge devices during their travel along the feed platform 77. As shown particularly in Figures 9 and 10, a pair of horizontal liquid-measuring cylinders 121 formed with peripheral collars 122 are bolted to a bracket plate 123 and extend through openings in the bracket plate to project beyond the forward bracket face 124.

The bracket plate 123 is formed with a flanged bottom 125 and is supported by this flanged bot-

tom parallel to and immediately above the forward longitudinal edge of the bed plate by a pair of spaced vertical frames 126 which extend transversely of the bed plate and are supported thereby.

Secured to the forward face 124 of the bracket plate are a pair of vertical cylinders 127 carried on the mounting plates 128 which abut the bracket face 124 and are provided with recesses 129 to receive the ends of the horizontal cylinders 121 projecting beyond the bracket face.

Each of the cylinders 127 is provided intermediate its length with a bore 130 extending transversely therethrough while communicating with this transverse bore are three passages 131 spaced ninety degrees apart, the one communicating with the upper cylinder chamber 132 and the opposite one communicating with the cylinder discharge mouth 133, while the intermediate passage communicates with the interior of the adjacent horizontal cylinder 121.

Rotatably arranged in the transverse bore 130 is a cylindrical valve element 134 which is bored to provide a hollow interior 135, while ports 136 arranged at ninety degrees from each other are provided in the valve wall and communicate with the hollow interior. The valve 134 is inserted into the transverse cylinder bore 130 and abuts against the shoulder 137 defined by the wall of the cylinder.

An extension 138 of reduced diameter projects outwardly from the valve beyond the outer cylinder wall and mounted on this extension 138 is a spring 139 constrained between the cylinder wall and the collar 140 on the outward end of the valve extension 138. This spring 139 serves to maintain the valve in position in the cylinder bore 130 abutting the shoulder 137.

The head end of the valve opposite to the end carrying the extension 138 is provided with a short central angular extension 141 through which the turning of the valve is accomplished.

The valves of the two cylinders are designed to operate in unison so that the extension of the left-hand valve looking from the front of the machine is provided with a recessed extension portion 142 which receives the angular extension 141 of the other valve to lock the two valves from relative rotation.

Threaded into the upper end of each of the vertical cylinders 127 is a supply tube 143 which connects with the bottom of the gravity tank 120, and arranged in this fluid supply tube is a manually operable valve 144.

The operation of the valve in the vertical cylinders 127 is such that when the valve is in one position the ports 136 communicating with the interior 135 thereof provides communication for the liquid between the upper cylinder chamber 132 through the upper passage 131 and the interior of the adjacent horizontal cylinder 121 through the passage 131 arranged at right angles to the upper passage.

Rotation of the valve through 90° will bring its ports 136 into alignment with the horizontal and lower passages 131 providing communication between the interior of the piston cylinder 127 and the discharge mouth 133 of the vertical cylinder.

The valve extensions 138 are plugged to prevent the liquid from discharging therefrom.

Slidably mounted in each of the horizontal cylinders 121 is a piston 145, the stem 146 of which extends rearwardly from the cylinder. Mounted between and above the center line of the horizontal cylinders 121 is an angular bar

11

147 of square cross section but arranged with its diagonals horizontal to and vertical to the bed plate. This bar 147 extends rearwardly from the bracket plate 123 across the bed plate and slidably arranged thereon is a slide 148 formed from a pair of V-plates bolted together and encompassing the bar.

The slide 148 carries a transversely arranged yoke member 149 which engages the ends of the piston stems 146 so that movement of the slide effects the operation of the pistons 145 in their cylinders.

The mechanism for operating the cylinder pistons and the valves 134 will now be described.

As shown in Figures 9 and 10, one of the vertical frames 126 has a vertical slot 150 therein, and slidably arranged in this slot is a block 151. The block 151 has a pivot shaft 152 extending laterally therefrom and on the end of this shaft a second block 153 is pivoted.

Mounted on this latter block 153 is a lever arm 154 formed with a central longitudinal slot 155 in which the block 153 is adapted to slide, the longitudinal edges of the slot engaging in grooves in the block edges.

The lower end of the lever arm 154 is pivotally connected to the upper end of an arm 156 in the form of a yoke, the lower end of which is pivoted on a shaft or stud 157 extending from the frame 126.

Mounted on the main shaft 9 extending longitudinally of the table, and through the frames 126 being supported in journals 158 formed integral with the frames, is a double internal cam member 159 formed with a cam groove 160 for operating the piston mechanism in one face, and a cam groove 161 for operating the valve mechanism in the opposite face. The pin 162 pivotally connecting the upper end of the yoke arm 156 to the lower end of the lever arm 154 extends beyond the yoke arm and carries a roller 163 at its end, with the roller engaging in the cam groove 160 of the cam 159. The upper end of the lever arm 154 is connected through an arm 164 to a bracket 165 carried by the slide 148.

The block 151 slidably arranged in the vertical slot 150 of the frame 126 carries a lateral extension 166 through which extends the threaded shank 167 of an operating screw 168 supported from the top of the frame 126 and controlled through the hand wheel 169. Thus by rotation of the operating screw 168 the block 151 is run up or down in the slot 150.

A locking screw 170 extending into the rearward edge of the frame 126 and adapted to enter the vertical slot therein serves to clamp the block 151 in the desired position to which it has been adjusted through the operation of the screw 168.

Upon rotation of the cam 159 the upper end of the arm 156 and the lower end of the lever arm 154 will be rocked back and forth in accordance with the lateral movement of the roller 163 engaging in the cam groove 160. The fulcrum of the lever arm 154 is the axis of the pivot shaft 152 on which the block 153 is pivoted and the lever arm rocks about this fulcrum to move the slide 148 back and forth on the rod or bar 147 through the arm 164 connected with the slide bracket 165.

By adjusting the position of the block 151 in its slot 150 and hence the position of the block 153 and its pivot shaft 152 the fulcrum of the lever arm 154 is adjusted to change the stroke of the piston 145.

12

The sliding arrangement of the block 153 in the central longitudinal slot 155 of the lever arm permits the smooth action of this arm during the rotation of the driving cam 159.

5 Journalled in the frame 126 opposite to its slotted counterpart in which the block 151 is mounted is a shaft 171 which extends through its supporting frame and has keyed thereto adjacent one end a short depending arm 172 which carries at its lower end a roller 173 engaging in the cam groove 161 of the cam 159.

Keyed adjacent the opposite end of the shaft 171 is an upwardly extending arm 174 pivoted to the upper end of which is a short arm 175, the outer upper end of which is keyed to a horizontal shaft 176 arranged in a journal carried by the bracket plate 123 and having an enlarged recessed end portion 177 adapted to engage the squared extension 141 of the valve member 134 to effect its rotation.

10 The arrangement of the cam 159 on the drive shaft 9 is such that during the interval the cartons are being fed forwardly to the filler mechanism the valve member 134 is rotated to provide 15 communication between the liquid supply tank 120 and the interior of the horizontal liquid measuring cylinders 121 at the same time the pistons 145 are being moved rearwardly to draw the liquid into cylinders 121.

15 During the interval that the cartons are stationed below the vertical cylinder discharge mouths 133 and the feed mechanism is on its return stroke the cam 159 operates to rotate the valve members 134 so that the interior of the 20 cylinders 121 is in communication with the cylinder discharge openings 133 while communication with the feed tank is cut off. Synchronized with this opening of the valves is the forward movement of the pistons 145 to discharge forcibly from the vertical cylinder mouths 133 into the 25 cartons stationed therebelow.

30 With the arrangement shown each carton is half filled in each of the two filler stations, that is, half of its contents is supplied by the first 35 filler station and the filling of the carton is completed at the second filler station. The amounts of liquid discharged in each case depends of course on the stroke of the pistons 145 which is regulated through the operating screw 168, changing the fulcrum of the lever arm 154.

35 Following the filling of the cartons they are next fed to the folding mechanism which folds their open mouths so that the mouths may be sealed at a subsequent station.

40 The folder mechanism for folding in the opposing sides of the carton mouth is shown in Figures 1, 3 and more particularly in Figures 17 to 19. As illustrated the folder mechanism is supported on an upright frame 178 which has a lateral extension 179 at its upper end, and arranged in the face or end of this lateral extension is a horizontal groove 180. Mounted in this groove is a bar 181 which extends transversely of the bed plate and beyond the forward edge thereof, 45 terminating above the carton feed platform 77.

Extending laterally from the end of the bars 50 are a pair of spaced shafts 182 on which are arranged gears 183 which intermesh as illustrated in Figure 17. Connected on the hubs of these 55 gears 183 or connected on separate hubs mounted on the gear shafts 182 and adapted to rotate with the gears are a pair of substantially C-shaped arms 184, the lower end of one of which is provided with a broad laterally extending jaw 60 member 185 formed with a right angularly in-

wardly extending upper lip portion 186, while the opposing arm 184 carries the co-operating jaw portion 187.

As illustrated in Figures 17 and 18, the arms 184 are oppositely arranged and their upper ends lie in parallel offset planes extending transversely of the bed plate, and the lower ends of the arms are bent towards each other at 188 and lie in the same vertical plane.

Secured to the outer arm 184 carrying the jaw member 185 through the pivot connection 189 is a link 190 formed with a series of notches 191 in its inner end and selectively engaged in one of these notches is the upper end of a bell crank 192 pivoted at 193.

Secured to the rearward end of the bell crank 192 by means of a pivot connection is a connecting rod 194 formed of a pair of threaded rod lengths engaging a turnbuckle 195 to permit adjustment of the effective length of the connecting rod.

A lever arm 196 pivoted at one end on a fixed pivot 197 is pivotally connected at its outer end to the rod device 194. Mounted on the side of the lever arm 196 intermediate its length and extending laterally therefrom is a roller 198 which engages in a cam groove 199 arranged in the face of an internal cam member 200 mounted on and keyed to the main drive shaft 9.

A spring 201 connected between the frame 178 and an extension 202 of the bell crank 192 serves to apply tension to maintain the outer end of the bell crank in an elevated position pulling up on the connecting rod 194 maintaining the roller 198 in engagement with the inner perimeter of the cam groove 199.

The operation of the folder mechanism is such that the connecting rod 194 is periodically rocked upwardly and then downwardly. The upward movement of the rod moves the link 190 longitudinally to effect the rotation of the outer arm 184 so that its jaw member 185 moves inwardly and simultaneously effecting through the meshing of the gears 183 the inward movement of the opposite arm carrying the co-operating jaw portion 187. After a fixed interval the connecting rod 194 is rocked downwardly and the jaw members 185 and 187 are separated. The action is timed so that the jaws are apart while the feed mechanism is feeding the filled carton forwardly between the arms 184 where it remains for the interval during which the feed mechanism is on its reverse stroke. It is during this interval that the filled carton is stationary that the arms 184 are rocked inwardly and the jaw members 185 and 187 to act to force the opposite sides of the carton in towards each other.

This action is co-ordinated with the action of the tucker mechanism to be described so that the folding of the carton mouth is accomplished at the one station.

The tucker mechanism illustrated in the general views Figures 1 and 3 and more particularly in Figures 13 to 16, is slidably arranged on a slide 203 extending transversely of the bed plate and supported on a bracket 204 secured to the upright folder frame 178.

Slidably mounted on the tucker slide 203 is the tucker body block 205 formed with a groove 206 adapted to receive the slide and interlock therewith. Secured to and extending forwardly of the block 205 are a pair of spaced bars 207 which have curved outwardly flaring ends 208.

Tucker arms 209 carry triangular shaped right angularly projecting blades 210 at their outer ends and these arms 209 are journaled in bear-

ings 211 arranged on the block and extend forwardly of the block above the spaced bars 207. The inner ends of the tucker arms 209 carry bevel gears 212 which mesh with the bevel gears 213 carried on a shaft 214 extending transversely of the block and supported in the journals 215.

On the outer end of the shaft 214 is a gear 216 which meshes with a toothed segment 217 journalled on a pin 218 extending through the hub of the toothed segment and through a depending lug 219 formed integral with the block 205.

A short extension 220 projecting from the hub of the toothed segment and integral therewith carries on its outer end a roller 221. A second extension 222 also projects from the hub of the segment 217 and has an offset portion 223 which carries a laterally projecting pin 224.

Tension springs 225 secured between this pin 224 and a pin 226 projecting from the side of the block 205 serves to rotate the toothed segment 217 so that the roller carrying extension 220 is rotated downwardly.

Pivoted secured to a lug 227 (see Fig. 16) arranged below the tucker slide 203 on the bed plate is an arm 228, to the upper end of which is pivoted a link 229, the end of which has a notch 230 (see Fig. 14) to receive the body of a pin 231 secured to and projecting from the block 205. This link 229, which is substantially horizontal extending rearwardly from the lever arm 228, effects the movement of the tucker block 205 on its slide 203 through movement of the arm 228 which carries a roller 232 intermediate of its length which engages the cam surface of the cam 233 secured to the main drive shaft 9.

A spring 234 secured between the bed plate and the arm 228 serves to maintain the roller 232 in engagement with its operating cam.

Thus upon rotation of the shaft 9 the tucker body block 205 is moved back and forth on its slide and has a stationary period at the forward end of its travel. During this back and forth movement of the tucker block the springs 225, which maintain the extension 222 of the toothed segment 217 in a forward position, maintains the blades 210 of the arms 209 in a vertical position through the rotation of the shaft 214 by the toothed segment by the intermeshing of the teeth of the segment and the gear 216.

During the interval at which the tucker block is in its forward position and at rest however, a quick-acting cam 235, also journalled on the drive shaft 9, engages the roller 221 carried on the toothed segment extension 220 to rock the roller-carrying extension upwardly rotating the toothed segment 217 to rotate the tucker arms 209, swinging their blades 210 to a horizontal position through the meshing of the gears 212 and 213. When the cam surface disengages the roller 221 the springs 225 of course function to rotate the toothed segment and the shaft 214 through the gear 216 to open or swing the tucker blades upright.

The action of the folder and tucker mechanisms is so timed that at the instant the filled carton is deposited by the feed mechanism beneath the open jaws carried by the arms 184 and opposite to the tucker slide 203, the tucker block 205 is moved forwardly on its slide by the arm 228, and the spaced bars 207 carried by the tucker block engage the sides of the carton to accurately position same to ensure accurate folding. The curved ends 208 of the bars 207 of course facilitate this positioning action.

Following the outward travel of the tucker

block and during the interval it is at rest, which of course coincides with the rest period of the carton while the feed mechanism is moving on its reverse stroke, the tucker blades 210 swing inwardly towards a horizontal position and due to their triangular shape form centre fold lines on opposite sides of the carton and fold the sides of the carton inwardly towards each other.

Synchronized with the movement of the tucker blades is the movement of the arms 184 which are swung inwardly through the longitudinal movement of the link 190 actuated through the bell crank 192 and the connecting rod 194 and lever arm 196 by the cam 200. With the inward movement of the arms 184 the jaw members 185 and 187 carried thereby forces the upper edges of the carton sides at right angles to the sides being cut by the tucker blades into contact. The jaw members then swing outwardly by the separation of the arms 184, the tucker blades 210 swinging upwardly and the tucker body block then slides rearwardly on the supporting slide and the folding operation is complete with the correct fold lines being formed in the carton.

In the event different carton sizes are to be used the tucker mechanism can be readily replaced by a similar unit designed to tuck or fold the carton to be used. This is simply accomplished by lifting the link 229 carried by the end of the arm 228 from the pin 231 projecting from the tucker block 205 and sliding the tucker block and the mechanism carried thereby rearwardly off its slide 203. The unit replacing the previous tucker unit is then simply arranged on the slide 203, pushed forwardly thereon and the link 229 swung down to engage its pin 231.

The spacing of the bars 207 carried by the tucker block and the size of the blades 210 will then be correct to properly fold the new size of carton.

The folder mechanism must of course also be adjusted for the new carton size and this is simply done through changing the effective length of the link 190 by changing the notch 191 in which the bell crank 192 engages. The effective length of the connecting rod 194 may also be adjusted through the turnbuckle 195 to finally adjust the desired extent of spread of the jaw-carrying arms 184.

Following the folding of the carton mouth by the folding and tucking mechanism described the cartons are fed through a folding attachment, illustrated in Figures 20 to 22. The purpose of this folding attachment is to compress the carton mouth, which naturally springs open somewhat when released by the folding mechanism, and to turn over or fold over the mouth while compressed.

The folding attachment comprises essentially a pair of bars 236 supported above and arranged longitudinally of the feed platform 11. The forward ends of these bars are twisted upwardly and outwardly as shown in Figures 20 and 21.

Secured to the uprights 237 from which the bars 236 are supported is a pair of bars 238 arranged edgewise of the bars 236 and curving inwardly and rearwardly towards each other until their distance apart corresponds to the thickness of the folded carton mouth from which point they extend rearwardly parallel to each other.

The outer of the bars 238 is bevelled towards its upper edge as at 239, while the rearward end 240 thereof is tapered rearwardly to a uniform reduced thickness. This outer bar 238 forms the guide about which the carton top is folded over

by the folding member, here shown as a wire 241 arranged above the bars 238 and curving from above the inward bar 238 across the opening between this bar and the opposing bar 238, then curving in toward the tapered rearward bar end 240, being parallel therewith for a portion of its length and terminating in a right-angular extension 242 which is secured by means of soldering to the outer of the bars 238.

In addition to curving in the horizontal plane, as shown in Figure 20, the wire 241 is inclined in a vertical plane as shown in Figure 21 with the rearward portion of the wire lying below the upper edge of the outer tapered bar 238.

The action of the folding attachment is such that the curved and twisted ends of the bars 236 serve to guide the cartons as they are fed along the feed table 11 into the space therebetween, compressing the carton mouth as illustrated in Figure 20.

On further forward movement of the carton it is fed between the bars 238, the curved forward ends of which again serve to properly locate the carton on the feed table and to further smoothly compress the carton mouth to the closed position.

The distance of the bars 238 above the feed platform is such that the upper edge of the carton mouth or carton lip projects above their upper edges and is engaged by the forward curved portion 243 of the wire 241, and upon the forward movement of the carton the carton lip is displaced laterally and is bent laterally and outwardly about the upper edge of the outer bar 238.

Since the wire 241 is inclined towards its rearward end and falls beneath the upper edge of the outer bar 238 it will, upon continued movement of the carton, act to fold the laterally extending carton lip downwardly against the bevel surface 239 of the outer bar 238 until the carton reaches the rearward tapered end 240 of the bar where the downturned carton lip portion will be forced to a substantially vertical downwardly projecting position at right angles to the portion contacting the upper edge of the bar to provide a doubled-over sealing mouth fold.

Thus the complete folding over of the carton mouth is accomplished without mechanical movement of the folding attachment but merely by the forward motion of the carton itself as fed by the feed mechanism previously described.

While I have shown a wire 241 for producing the folding, it will be understood of course that the inner bar 238 could be formed with a flange portion to extend over the outer bar 238 and downwardly below the upper edge of the outer bar end 240 to accomplish the same purpose as the folding wire.

Following the folding over of the carton mouth by the folder attachment the carton is then ready to be hermetically sealed. The cartons may then be sealed either by the use of a stitching or stapling device, which staples the folded-over carton mouth and a cold sealing device which subsequently applies pressure to the carton mouth after stapling to bond the wax impregnated surfaces of the folds of the folded-over carton mouth through pressure. Alternatively and preferably the hermetic seal may be accomplished through the use of a heat-sealing device to be described.

The stitcher or stapler device, generally designated as S, may be of any well known type found on the market, such for instance as the

stapler shown and described in United States Patent 2,063,345, December 8, 1936, to H. T. Scott.

Since this stapling device is old and is not of my invention detailed drawings of same are not shown. In the general views, Figures 1, 3 and 4 however the stapling devices S of which there are 2, are shown mounted on a slide 244 arranged on a suitable frame or standard 245 supported on the bed plate 1.

The wire from which the staples are formed is drawn from the spools 246 supported above the bed plate and the wire feed mechanism is generally indicated at 247.

During the periodic forward movement of the cartons each carton is deposited with its folded-over mouth projected between jaws formed in the heads 248 of the staplers which carry the mechanism for cutting the wires from the spools 246 into the required length to form the staples.

The mechanism for bending the wire into the form of the staple and for forcing same through the folds of the carton mouth and the mechanism for turning in the outer ends of the staples to clamp the mouth closed is all old and no description or illustration is deemed necessary.

The operation of the stapler mechanisms is effected through cams 249 arranged on the main drive shaft 9. The action of the staplers is of course synchronized so that the stapling is effected during the interval that the carton is properly located between the jaws of the stapler while the feed mechanism is making its return stroke.

Following the stapling of the carton it is fed forwardly to the cold-sealing mechanism illustrated in Figures 23 to 26. As illustrated in these figures, the cold sealer is supported on a frame 250 mounted on the bed plate 1, and mounted on the top of this frame by the bolts 251 is a rearwardly curved and upwardly extending yoke frame 252.

Extending through and journalled in the upper ends of the frame 252 is a horizontal shaft 253 which extends longitudinally of the table, and rotatably mounted on this shaft 253 is a web frame 254 provided with depending hub portions 255 engaging the shaft and extending forwardly from the hub portions beyond the forward edge of the bed plate in a substantially horizontally plane.

The horizontal web 256 of the frame 254 is cut away at the forward and rearward ends to provide the notches 257 and 258 respectively between the vertical webs 259 formed with bearing bosses 260 at their outward ends in which are journalled a shaft 261 extending transversely between the vertical webs.

Keyed on this shaft 261 is a toothed segment 262 which engages a rack member 263 slidably arranged in a groove 264 in a bottom plate 265 bolted to the extensions 266 depending from the bearing bosses 260.

To maintain the rack member in the groove 264 bars 267 secured to the bottom plate 265 by means of suitable bolts engage over the notched rack edges 267. The forward edge of the rack member 263 forms one of the co-operating jaws 268 of the sealer mechanism and this jaw member is adapted to co-operate with the forward edge 269 of a slide 270 slidably mounted between the depending side webs 271 of the frame 254 and supported on the upper surface of a plate 272 which is itself slidably supported on a bottom plate 273 bolted to the bottom edges of the side webs 271.

The plate 272 and the slide 270 act independently through the operation of a pair of rods

274 operating through a transverse bar 275 secured to the slide 270 and against which compression springs 276 surrounding the rods 274 abut. Thus forward motion imparted to the slide 270 is transmitted to the plate 272 through the compression of the springs 276, rearward motion of the slide 270 relative to the plate 272 is limited by the stop nuts 277 threaded on the outer ends of the rods 274.

10 The plate 272 has a lateral extension 278 at its forward end and this lateral extension has its forward edge smoothly curved, as shown in Figure 25.

15 The bottom plate 265 supporting the rack member 263 is also formed with an opposing projection 279 opposite the extension 278 and this projection is curved similarly to the extension 278 whereby the curved surfaces of the members 278 and 279 serve to guide the folded mouth of a 20 carton being fed forwardly by the feed mechanism accurately between the rack member 263 and the slide 270.

25 To accommodate the staples securing the carton mouth in the folded position the slide 270 is formed with an insert 280 extending across its forward face and this insert has a groove or notch 281 to receive the staples.

30 Journalled in a recess 282 formed in the inner end of the slide 270 is a roller 283 adapted to engage a cam 284 mounted on the shaft 253 journalled in the yoke frame 252, and this cam serves to reciprocate the slide back and forth between the side webs 271 of the horizontal frame 254.

35 To maintain the roller of the slide 270 into engagement with its cam the slide is provided with laterally projecting pins 285 which extend through slots 286 in the side webs 271, and secured between these pins and the right angular extensions 287 of arms 288 secured to the webs 271 are coiled tension springs 289. Thus the slide 270 is pulled rearwardly under the tension of the springs 289 and its roller 283 is held in firm engagement with the cam 284.

40 To support and maintain the web fram 254 in its desired substantially horizontal relation, which can be adjusted as desired, is a threaded spindle 290 threaded in a forwardly extending bracket 291 carried by the frame 250. The upper end of this spindle engages the under surface of the bottom plate 273 of the web frame and adjustment of the spindle by means of a head portion 292 provides accurate adjustment of the height of the jaws 268 to properly engage the carton mouth.

45 The movement of the jaws 268, which is in effect the inner edge of the rack member 263, is accomplished through a cam 293 arranged on the shaft 253 and engaging a roller 294 carried on one arm of a bell crank 295 pivoted on the web frame 254. This bell crank is adapted to be 50 rocked by the rotation of the cam 293, and the rocking action is transmitted through a horizontal rod 296 to a short extension 297 keyed on the transverse shaft 261 journalled between the bearing bosses 260 formed at the outward end of the frame 254.

55 The rotation of the rear transverse shaft 253 carrying the cams 284 and 293 is effected through the intermeshing of gears 298 and 299 keyed to the shaft 253 and main drive shaft 9 respectively.

60 The synchronism of the sealer mechanism is such that the rack 263 and slide 270 are apart at the instant the carton is being delivered between their co-operating edges, and the curved surfaces 75 of the projections 278 and 279 accurately guide

the carton into position between these jaw members.

Following the completion of the forward stroke of the feed mechanism delivering the carton with its mouth between the sealer jaws and during the interval in which the feed mechanism is on its return stroke, the slide 270 is urged forwardly by its cam 284 to compress the upper portion of the carton sealing lip or fold above the staples against the rack 283, the staples entering the notch 281 in the slide forward face. The forward edge of the plate 272 under actuation of the compression springs 276 is urged into engagement with the carton lip or fold below the staples.

Following the forward motion of the slide 270 the rack member 263 is moved rearwardly in its slide groove 264 through the rotation of the toothed segment 262 as its shaft 261 is rocked upon rocking of the bell crank 295 by its roller engaging cam 293.

This movement of the rack applies a very positive pressure to the folded carton sealing lip, squeezing it against the forward edge of the slide 270 which on further inward motion of the sliding rack moves rearwardly. The slide plate 272 beneath the slide 270 however remains in its forward position under the action of the springs 276 compressed between the slide-carrying bar 275 and the slide plate.

The sealer produces a very positive pinching action in this manner and under this pinching pressure the wax-impregnated folded carton surfaces, which form the sealing lip, are integrally bonded together, forming an hermetic seal.

As an alternative to the stapling mechanism and cold seal mechanism the sealing mechanism illustrated in Figures 27 to 32 may be used. This mechanism produces a hot seal and dispenses with the necessity of using the stapler or stitching mechanism and is therefore preferably employed on my machine. The cold seal mechanism of course is also dispensed with.

As illustrated, a suitable support frame 300 is mounted on the bed plate 1 and extending substantially horizontally outwardly therefrom are a plurality of jaw carrying arms 301 formed with journal bosses 302 at their inner ends and with spaced outwardly projecting bearing bosses 303 on the outer ends thereof.

The forward ends of the arms 301 are provided with angled surfaces 304 in which are formed the recesses 305, as shown in Figure 29, and abutting the angled surfaces are the substantially triangular-shaped jaw members 306, each of which is formed with a recess 307 in its rearward face and with a notch to receive the jaw insert 308 in its forward vertical face. A plate 309 extending from the under surface of each of the arms 301 serves to maintain the jaw member 306 and its insert 308 in position.

These arms 301 are in the form of web frames which define the rectangular wells 310 on their upper surface, and these wells are closed by the plates 311.

Journalled between the spaced bosses 303 carried by the arms 301 is a shaft 312 on which is mounted between each pair of the bosses 303 the opposing jaw-carrying members 313 which are generally T-shaped with the body of the T being journalled on the shaft 312 and the head extending to the width of the spaced bosses 303.

The lower inner surface of the heads of the members 313 are angled as at 314 oppositely to the angled surfaces 304 of the arms 301, and

recesses 315 are provided in the angled surfaces 314 similar to the recesses 305.

Secured to the angled surfaces 314 of the outer jaw-carrying members 313 are the triangular shaped jaw members 316 which correspond to the jaws 306 and have recesses 317 in their rearward surface registering with the recesses 315 and with inserts 318 inset in their forward faces and opposing the inserts 308 of the opposing jaw members.

Formed on the upper surface of the outer jaw-carrying members 313 are wells 319 over which engage the cover plates 320.

In operation the outer or opposing jaw-carrying members 313 are adapted to move into and out of cooperative relation with the arms 301, and this movement is effected through the following mechanism.

Journalled in the bosses 302 at the inner ends of the arms 301 is a shaft 321 to which is secured a bell crank 322 carrying on its lower end a roller 323 engaging a cam 324 mounted on the main drive shaft 9 extending longitudinally of the bed plate.

Pivotsly connected to the upper end of the bell crank is an adjustable connecting rod 325, the length of which can be changed by threading the body portion 326.

The outward end of the connecting rod 325 is pivotsly connected with an upward extension 327 carried by one of the outer jaw members 313.

Rocking of the bell crank 322 thus rocks the outer jaw-carrying member into and out of clamping cooperative relation with the opposing jaw-carrying arm 301.

While Figure 28 shows the operating mechanism for one particular jaw as formed by one of the jaw-carrying arms 301 and its opposing jaw-carrying member 313, the remainder of the jaws are operated similarly through the rocking of the shaft 321, their connecting rods 325 being pivotsly connected to their upward extensions 327 carried by the outer jaw members and to the extensions corresponding to the upward arm 328 of the bell crank 322 arranged on the shaft.

The jaws 306 and 316 carried by the arms 301 and members 313 respectively are heated by the electrical heaters 329 inset in the recesses 307 and 317 arranged in the rearward surfaces of

the jaw members and projecting into the recesses 305 and 315 arranged in the angled faces 304 and 314 of the jaw-carrying members 301 and 313 respectively.

The leads 330 from the heaters 329 lead through the inner walls of the recesses in which they are housed and into the wells 310 and 319 of their respective jaw-carrying members, and these wells form the junction boxes for suitable feed connections 331.

As the wiring for the heaters is conventional no further details of the wiring circuit are deemed necessary.

To gain access to the terminals 332 located in the wells 310 and 319 the cover plates 311 and 320 may conveniently be removed.

To control the heating effect of the heaters and the temperature to which the jaw members 306 and 316 reach a suitable thermostat 333 is located within an opening 334 in the jaw members 306.

Thus in the operation of the machine the cartons fed by the feed mechanism from the folding attachment to the first set of jaws of the heat sealer, termed the pre-heat jaws, the action of the cam mechanism 324 operating the outer

Jaw carrying members 313 through the bell crank 322 and the connecting rod 325, is such that the outer jaw member of each of the jaw pairs is swung away from the opposing jaw during the instant that the carton is being fed forwardly therebetween.

During the interval the carton is at rest and the feed mechanism is on its return stroke the outer jaw-carrying member 313 of each jaw pair moves inwardly to clamp the folded-over carton lip or mouth between the heated jaws 306 and 316. Thus heat and pressure is simultaneously applied to properly close and tightly compress the folded-over carton lip, and the heat is sufficient to effect a softening of the waxy coating of the carton so that the contacting surfaces forming the fold of the carton mouth become integrally bonded through the bonding of their plasticized coatings.

The first two sets of jaw members effect the primary seal of the carton. To prevent the soft seal from pulling apart as the outer jaws 316 are moved away from the clamping position the jaw inserts 308 and 318 have a smooth carton-engaging surface which will provide no adhesion with the waxy carton coating. These jaw inserts are also shown projecting slightly beyond the clamping surface of the jaws themselves to provide a tighter clamping action therebetween to facilitate the heat and pressure effected seal.

Following the primary seal obtained with the pre-heat jaws the carton is fed forwardly again between the final pair of jaw members for the final seal.

Thus when the carton reaches the final set of jaws it is sealed but is still hot and the waxy coating is in a plasticized state. The final seal is therefore obtained by applying further heat and pressure to the folded carton lip or mouth, further bonding the surface coatings to effect a seal which will be very strong and hermetic.

However, before the cartons are to be handled it is desirable that the seal be cooled to set the plasticized wax with the surfaces bonded as provided by the final seal. To accomplish this cooling of the carton mouth the mechanism shown in Figures 27 and 30 is utilized.

As illustrated an angle bracket 335 extends laterally from the arm 301 of the final sealing jaws and secured at spaced intervals to the forward face of this angle bracket are web brackets 336 formed with journal bosses 337 on their outward ends and with a depending portion 338 which support a jaw member 339.

Journalled between the web brackets 336 in their journal bosses 337 is a shaft 340. Mounted on this shaft 340 adjacent each of the brackets 336 is a depending jaw-carrying member 342 having a lateral projection 343 at its lower end, and secured to this projection is a jaw member 345 adapted to co-operate with the opposing jaw member 339 secured to the depending portion 338 of the bracket.

Secured to the shaft 340 and extending rearwardly therefrom is a rod 346, the rearward end of which is engaged by a spring 347 which is anchored at its upper end to the angle bracket 335. This spring acts through the rod 346 to rotate the shaft 340 to bring the jaw member of the depending jaw-carrying member 342 into co-operative relation with its opposing jaw member 339.

The rotation of the shaft to effect the opening movement of the jaw-carrying member 342 is effected through the engagement by a roller

348 carried on the outward end of an arm 349 secured to the shaft with a bevelled or inclined surface formed at one end of the head of the T-shaped outer jaw-carrying member 313 of the final sealing jaws. Thus as this member 313 is rocked upwardly and opening the jaws of the final seal jaws, the shaft 340 is also locked through the arm 349 to open the jaws 345 and 319.

Secured to the underside of the outward end 10 of the web brackets 336 is a pipe 351 which extends beyond the brackets and terminates in an extension 352 which has a plurality of spray orifices 353 therein.

As shown in Figure 30, the pipe 353 is inset in 15 a groove 354 in the under surface of the brackets 336 to provide a large contact area between the brackets and the pipe so that a large amount of heat may be transferred from the brackets through the pipe which is adapted to carry a cooling liquid supplied thereto through a suitable coupling 355.

Thus following the final seal the cartons are 20 fed between the jaws 339 and 345 which of course are synchronized together with the heat sealer mechanism to open to receive the cartons and to close upon completion of the forward movement of the carton and during the interval the feed mechanism is on its return stroke, and these 25 jaw members act to exert pressure on the sealed carton mouth or lip and at the same time are adapted to convey a large proportion of the heat from the carton lip to the liquid or water flowing in the cooling tube or pipe 351. Thus a cooling of the seal is rapidly effected and the plasticized bonded waxy surfaces begin to rapidly 30 "set."

Following this clamping and cooling action the 35 cartons are fed forwardly again beneath the extension 352 arranged at the end of the pipe 351, and water is sprayed from the orifices 353 therein over the carton, further increasing the cooling 40 so that the seals will be sufficiently cool by the time the cartons are removed that they will not be damaged by handling.

Following the cooling the heat seal is extremely 45 strong and will serve to adequately protect the carton contents.

Following the completion of the seal and the 50 cooling thereof the cartons are deposited on the belt conveyor 81 which moves them to the end of the machine where they may be picked up by an operator or transferred to any conveyor system desired which will convey them to the frames in which they may be packed and shipped directly to the delivery wagon.

From the foregoing it will be therefore seen 55 that the complete operation of removing a carton from the carton stack on the magazine to the finally filled and sealed carton delivered by the conveyor belt is entirely automatic with the timing of the various mechanisms being set to operate on the carton during the period it is at rest on the return stroke of the feed mechanism.

The whole machine is extremely compact and 60 all the mechanisms operate positively so that there will be no waste and each carton will be properly filled and sealed.

Thus the machine will have a very high capacity and its maintenance and operating costs 65 will be extremely low, the single motor 4 serving to operate the entire machine mechanisms.

In addition the machine mechanisms are very 70 readily adjusted to accommodate various sizes of cartons for packaging half pints, pints or 75 quarts or other quantities. With the various ad-

justments the feed mechanism does not need to be disturbed, it being merely necessary to raise the feed platform 11 by adjusting the bars 18 in their clamps 19 to bring the carton mouth into proper position relative to the folding and sealing mechanisms.

The adjustments to the magazine to accomplish the various sizes of carton is quickly accomplished through the adjustments provided and the amount discharged by the filler mechanism is also very readily adjusted by moving the block 151 through the hand wheel control 168.

In the folding operation the tucker mechanism can be quickly removed from its slide and replaced by the required size of tucker and the clamping arms of the folder can be readily adjusted through adjustment of the length of the link 180.

Where the stapler mechanism and the cold seal are used the required size of stapler can be quickly inserted in position and the cold seal mechanism can be adjusted to provide the proper sealing pressure.

Where the cold seal and stapler are dispensed with for the hot seal mechanism the pressure of the sealing jaws can be readily adjusted through the adjustment of the connecting rods 325.

These adjustments can be very readily carried out without requiring any extensive delay in the operation of the machine.

In addition the various frames supporting the component mechanisms can be readily removed for shipping and for convenience in handling and in the event that one of the mechanisms should not operate correctly it can be quickly replaced without requiring the dismantling of the complete machine.

It will therefore be appreciated that I have provided an extremely reliable and efficient unitary machine in which the synchronism and co-operative relation of the various mechanisms are combined into an integral unit capable of complete operation of packaging milk or other liquids in paper type cartons.

What I claim as my invention is:

1. In a liquid packaging machine the combination with a bed plate, a feed platform extending longitudinally of the bed plate, a plurality of devices spaced along the bed plate above said feed platform to fill and seal liquid-receiving cartons fed thereto, of a magazine for holding a stack of liquid-receiving cartons comprising a frame supported on said bed plate, carton-engaging rails swingably supported on said frame for movement inwardly and outwardly relative each other and adapted to periodically grip and release said carton stack, means to operate said magazine rails, latch means supported on said magazine frame, means periodically operating said latch means to release the lowermost carton of said stack, gripper means supported by said bed plate and arranged to periodically withdraw the lowermost carton of said carton stack from said magazine at the instant said lowermost carton is released by said latch member and to deposit the carton withdrawn on said feed platform means to operate said gripper means periodically, and feed means supported by said bed plate to periodically advance the cartons deposited on said feed platform.

2. In a liquid packaging machine a bed plate, drive shaft means journaled on said bed plate, a motor operatively connected to operate said drive shaft means, a feed platform supported by

and extending longitudinally of said bed plate adjacent the forward edge thereof, an upright frame mounted on said bed plate adjacent one end thereof, a frame in the form of a reverse C supported by said upright frame with its plane angularly inclined relative the vertical and extending forwardly beyond the forward edge of said bed plate, curved arms pivoted adjacent their ends on said C-frame, longitudinal rails secured to the free ends of said arms and extending right angularly to the plane thereof and to the plane of said C-frame and inclined angularly upwardly, said rails being arranged in opposing pairs forming a magazine adapted to receive a stack of empty liquid-receiving cartons therebetween, link means inter-connecting said pivoted arms for co-ordinating movement of said arms, cam-operated means connected with one of said arms and operated through said drive shaft means to effect a periodic inward and outward movement of said rails to grip and release a carton stack placed therebetween, gripper means supported from said bed plate and operated through said drive shaft means to periodically withdraw the lowermost carton of said carton stack from the lower ends of said rails and to deposit same on said feed platform, and feed means supported by said platform and operated through said drive shaft means to periodically advance the cartons deposited on said feed platform.

3. A device as claimed in claim 2 in which the rails carried by said pivoted arms are mounted on slides arranged on the free ends of said pivoted arms and extending right angularly thereto, said slides being movable to adjust the spacing between said rails to accommodate various sizes of cartons inserted therebetween.

4. A device as claimed in claim 2 in which latch means are arranged below said C-shaped frame, said latch means being adapted to engage the lowermost carton of a carton stack inserted between said rails, and cam-operated means connected with said latch means and operated through said drive shaft means to periodically operate said latch means to release said lowermost carton as the carton is gripped by said gripper means.

5. A device as claimed in claim 2 in which a latch member is arranged below the lower ends of said rails and adapted to engage the lowermost carton of said carton stack to release said stack from moving downwardly while said rails are swung outwardly releasing said stack, cam-operated means connected with said latch member and operated through said drive shaft means to operate said latch member periodically to release the lowermost carton, and means for rendering said latch-operating means inoperative.

6. In a liquid packaging machine a bed plate, drive shaft means supported in journals mounted on said bed plate and extending longitudinally thereof, a motor operatively connected to drive said drive shaft means a magazine assembly for holding a stack of liquid-receiving cartons arranged at one end of said bed plate, a feed platform supported by and extending longitudinally of said bed plate, a gripper arm pivoted below said magazine assembly, a jaw carried at the end of said gripper arm, means operated through said drive shaft means to reciprocate said gripper arm about its pivot point through a predetermined arc to carry cartons from said magazine assembly to said feed platform, means carried by said magazine assembly to operate said jaw to

grip the bottom of the lowermost carton of said carton stack, cam means supported adjacent said feed platform for opening said jaw to release said carton at the feed platform, and feed means supported from said bed plate and operated through said drive shaft means to periodically advance the cartons delivered to said feed platform.

7. A device as claimed in claim 6 in which the means for operating said gripper arm comprises a fly wheel driven by said drive shaft means, and a pitman pivoted eccentrically to said fly wheel and pivoted to said gripper arm.

8. A device as claimed in claim 6 in which said jaw carried by said gripper arm comprises a fixed jaw member and a pivoted jaw member, a spring for urging said pivoted jaw member into gripping relation with said fixed jaw member, a roller carried by said pivoted jaw member, said roller being adapted to co-operate with said cam means supported adjacent said feed platform to open said jaw by swinging said pivoted jaw member away from said fixed jaw member, said means carried by said magazine assembly for operating said jaw comprising a cam projection for engaging said roller, and means operated through said drive shaft means to operate said cam projection to first open said jaw to receive the bottom of the lowermost carton and to then release said jaw to grip said carton.

9. A device as claimed in claim 6 in which latch means is pivotally supported adjacent the bottom of said magazine assembly to maintain said carton stack in said magazine, cam-operated means operated by said drive shaft means for periodically operating said latch means to release the lowermost carton as said carton is gripped by said gripper arm, and cam-operated means operated through said drive shaft means for gripping the remainder of said carton stack while said lowermost carton is released by said latch means and is withdrawn by said gripper arm.

10. In a liquid packaging machine a bed plate, drive shaft means supported in journals mounted on said bed plate and extending longitudinally thereof, a motor operatively connected to drive said drive shaft means, a magazine assembly for holding a quantity of empty liquid-receiving cartons arranged at one end of said bed plate, a feed platform supported from said bed plate and extending longitudinally thereof adjacent the forward edge, means for depositing a carton from said magazine assembly onto said feed platform, a longitudinally slideable rock shaft extending longitudinally beneath said feed platform, a second longitudinally slideable rock shaft supported from said bed plate and extending parallel to said first-mentioned rock shaft beneath said feed platform, carton-engaging means carried by said rock shafts, means operated by said drive shaft means to reciprocate said rock shafts longitudinally, toothed members carried by said rock shafts and adapted to intermesh to translate motion from one of said shafts to the other, a yoke member carried by one of said rock shafts, a block slidably arranged in said yoke member, a rock shaft on which said block slides, and cam means for operating said last-mentioned rock shaft and driven through said drive shaft means, to rock said carton-engaging means into carton-engaging relation upon longitudinal movement of said rock shafts in a direction to advance said cartons along said feed platform and to rock said carton-engaging means out of carton-engaging relation upon reverse longitudinal movement of said rock shafts.

11. In a liquid packaging machine, the com-

bination with a bed plate, a feed platform extending longitudinally of the bed plate and a plurality of devices spaced along the bed plate above said feed platform to fill and seal liquid-receiving cartons delivered therewith, of a magazine arranged at one end of said bed plate to support a supply of liquid-receiving cartons, means for periodically depositing a single carton from said supply onto said feed platform, and continuously operating means for periodically advancing deposited cartons along said feed platform from one device to another to be filled and sealed, said latter means comprising a horizontal rock shaft mounted for longitudinal reciprocation through a stroke having a length corresponding to the spacing between said devices, carton-engaging arms fixed to said rock shaft, means to rock said rock shaft to bring said carton-engaging arms into and out of carton-engaging relation, and means connected with said rock shaft to reciprocate same longitudinally, said reciprocating means connected with said rock shaft operating to move said rock shaft in a direction to advance the cartons delivered to said feed platform while said carton-engaging arms carried by said rock shaft are in carton-engaging relation and to return said rock shaft while said carton-engaging arms carried thereby in and out of carton-engaging relation.

12. In a liquid-packaging machine, the combination with a bed plate, a feed platform extending longitudinally of the bed plate and a plurality of devices spaced along the bed plate above said feed platform to fill and seal liquid-receiving cartons delivered thereto, a magazine arranged at one end of said bed plate to support a supply of liquid-receiving cartons, means for periodically depositing a single carton from said supply onto said feed platform, and continuously operating means for periodically advancing the deposited cartons along said feed platform from one device to another to be filled and sealed, said latter means comprising a pair of rock shafts extending longitudinally beneath said feed platform and mounted to reciprocate longitudinally through a stroke corresponding to the distance between said devices, carton-engaging means carried by said rock shafts and projecting above said feed platform on opposite sides thereof, toothed members carried by said rock shafts and intermeshing to translate motion from one rock shaft to the other, means for rocking said rock shafts to move said carton-engaging means into and out of carton-engaging relation, and means to reciprocate said rock shafts longitudinally and timed to move said rock shafts in a direction to advance the cartons delivered to said feed platform while said carton-engaging means carried by said rock shafts is in carton-engaging relation and to return said rock shafts while said carton-engaging means carried thereby is out of carton-engaging relation.

13. In a liquid packaging machine, the combination with a bed plate, a feed platform extending longitudinally of the bed plate, a plurality of devices spaced along the bed plate above said feed platform to fill and seal liquid-receiving cartons delivered thereto, and means for delivering cartons to said feed platform, of means for advancing cartons delivered to said feed platform to successively position the cartons beneath each of said devices for a period for said devices to perform their function, said latter means comprising carton-gripping elements rockable into and out of carton engagement and mounted to

reciprocate along their axes of rock through a stroke corresponding in length to the distance between said devices.

14. A means for advancing articles a predetermined distance along a feed platform at periodic intervals, comprising in combination with the platform, of a pair of rock shafts supported to reciprocate longitudinally through a stroke corresponding to the desired predetermined length of movement of said articles, means reciprocating said rock shafts, article-engaging means carried by said rock shafts, and means to rock said rock shafts to swing said article-engaging means into adjacent relation to engage an article while said rock shafts are being reciprocated longitudinally in a direction to advance said article and to swing to a position out of article-engaging relation to release the article while said rock shafts are being reciprocated in a reverse direction following advance of the article.

15. In a liquid packaging machine, the combination with a bed plate, a magazine for retaining a supply of liquid-receiving cartons supported on said bed plate, and means for feeding cartons from said supply longitudinally of said bed plate, of a liquid supply tank supported by said bed plate, a plurality of valve housings communicating with said supply tank and having discharge openings arranged above the path of travel of said cartons fed from said magazine by said feed means, a plurality of liquid measuring cylinders communicating with said valve housings, valve means arranged in said valve housings and operable to direct liquid from said supply tank to the interior of said liquid measuring cylinders and from said cylinders to said discharge openings to fill the cartons fed therebeneath, pistons reciprocably arranged in said cylinders to draw in a measured quantity of liquid from said supply

tank and to subsequently force the measured quantity of liquid out said discharge openings, means for reciprocating said pistons, adjustable means for regulating the stroke of said reciprocating means, and means for operating said valve means, said means for reciprocating said pistons comprising a slide reciprocally mounted and connected with said pistons, a lever arm having a longitudinal slot therein, a block slidable in said slot, a pivot shaft extending through said block and supporting same for pivotal movement, a rock arm, a pin pivotally connecting said rock arm and the lower end of said lever arm, a cam having a cam groove in which said pin engages to rock said rock arm and said lever arm about said pivot shaft, means operating said cam, and an arm connecting the upper end of said lever arm and said slide to reciprocate same, said pivot shaft being adjustable in position to alter the length of stroke of said slide.
